DESIGN FOR A LETTER OPENER

Edward K. Madan, Maplewood, N. J.

Application December 7, 1944, Serial No. 116,790

Term of patent 7 years

(Cl. D74—1)

To all whom it may concern:

Be it known that I, Edward K. Madan, a citizen of the United States of America, residing at Maplewood, in the county of Essex and State of New Jersey, have invented a new, original, and ornamental Design for a Letter Opener, of which the following is a specification, reference being had to the accompanying drawing, forming part thereof.

In the drawing:

I claim:

The ornamental design for a letter opener, as shown.

EDWARD K. MADAN.
